ELECTRIC INCINERATOR HEATING UNIT

Harry Friedberg, Cleveland, Ohio, assignor to Waste King Corporation, Los Angeles, Calif., a corporation of California

Application January 4, 1955, Serial No. 479,778

4 Claims. (Cl. 219—19)

The present invention relates to electric incinerators and, more specifically, to an electric incinerator structure embodying a new and improved heating assembly.

The invention provides a heating assembly which is inexpensive and easy to service and replace. The assembly is projected into the interior of the refuse chamber of the incinerator to more effectively heat the contents thereof. The operation of the unit is such as to maintain steady heating and drying out of the contents of the refuse chamber at normal relatively low radiating temperatures while causing rapid drying out and burning away of any refuse which may tend to interfere with the heating and drying out of the majority of the refuse by becoming packed directly around the unit.

The invention comprises a heating assembly in which a cantilever housing encloses a similarly extending heating element which is spaced from the housing. The housing normally absorbs and re-radiates at a reduced temperature the heat produced by the heating element. When directly contacted by refuse, the housing quickly rises in temperature. Housing temperature temporarily approaches the temperature of the heating member to dispose of the contacting refuse. The housing thereupon returns to normal temperature and continues to radiate throughout the refuse chamber under conditions consistent with efficient performance and long service life.

The objects and advantages of the invention will be more fully understood from a reading of the following specification which, together with the accompanying drawings, describes one specific embodiment of the invention.

In the drawings:

Figure 1 is a view in cross-section of a refuse incinerator including a heater assembly embodying the invention.

Figure 2 is a view taken from line 2—2 in Figure 1.

Figure 3 is a detailed view of the heating assembly seen in Figure 1, with one of the insulating supports removed.

Figure 4 is a view taken from line 4—4 in Figure 3.

Figure 5 is a view taken from line 5—5 in Figure 3.

The heater assembly contemplated by the invention is shown in Figure 3 in position on the panel or wall 10 of a chamber, the contents of which the unit is intended to heat. The unit comprises a housing 11 in which is received a heating element 12. The housing is brazed or welded to the flange 13 of a mounting plate 14. The mounting plate 14 is bolted to the wall 10 by bolts which may pass through spacers 15 (Figure 4), the plate 14 being thus supported in spaced relation from the wall 10. The bolt passing through the upper spacer 15 also anchors a detent member 16 which is positioned on the outer side of the plate 14.

Received within the open end of the housing 11 are a pair of ceramic insulating support members 17 which are suitably grooved to receive and support the ends of the heating element 12. The terminals 18 of the heating

2

element 12 are fixed to tabs 19 which are tapped to receive binding post screws 20 to which are secured the power leads 21. The tabs 19 and binding post screws 20 are accommodated in the enlarged pockets 22 formed in the members 17.

The members 17 are each formed with a semi-circular boss 23 (Figures 2—4), the bosses 23 together making up a circular plug received within the open end of the housing 11. The members 17 each have ears or flanges 24. 5 The flanges 24 are adapted to be moved into and out of interlocking relationship with the detent member 16 by rotation together of the two members 17.

In Figure 1 is shown an incinerator in which is employed the heating unit described above. The incinerator has a refuse chamber 40, a casing 41 surrounding the refuse chamber and spaced therefrom to define an air jacket space 42, a grate 45 at the bottom of the refuse chamber 40, and an ash drawer 46 below the grate 45. The refuse chamber 40 is vented to a flue 48, to which 15 the air jacket space 42 may also be vented through an opening or gap 49. An access door 44 is provided in the front of the casing 41. The power leads 21 run under the incinerator as shown and are connected to a suitable junction box 25.

20 25 The charge to be disposed of is deposited in the refuse chamber 40 by temporarily lifting a lid 50, and the charge is held away from the flue outlet by means of a perforated screen or grate 52. Fiberglass insulation 53 may be included around the inside of the casing 41 to 30 maintain the outside of the casing cool. It will be seen that the housing 11, projecting as it does as a stubby cantilever into the refuse chamber 40, provides a central source of heat while, at the same time, allowing ready settling of the refuse with a minimum of packing or 35 lodging against the heating unit.

With the heating unit 12 operating at a temperature of about 1000° F., the housing 11 attains a temperature of about 500—600° F. and radiates heat throughout the refuse at this normal temperature to dry out the refuse 40 mass prior to final burn-off. Any refuse which may become packed or lodged against the housing tends to block off radiation throughout the refuse chamber from the housing. Because of this cutting-off of radiation, the temperature of the housing 11 quickly approaches that 45 of the heating element 12 and the packed or lodged refuse is quickly dried out and either falls away from the housing 11, being no longer damp and sticky, or ignites and burns off. After the removal of packed or lodged refuse, the entire housing resumes normal radiation and 50 normal temperature.

It is to be noted that the heating element 12 and supporting base members 17 may be easily removed from the incinerator through the access door 44. The screw holding the detent member 16 is slightly loosened, the members 17 are rotated until the flanges 24 clear the detent member 16, and the sub-assembly is withdrawn to the extent allowed by the leads 21.

While a specific embodiment of the invention has been disclosed above, many details of the embodiment are not necessary to the invention. The scope of the invention is defined in the following claims.

What is claimed is:

1. An incinerator comprising a refuse chamber to receive and contain refuse to be incinerated, said refuse chamber having a bottom wall and side walls and cover means, a hollow metallic body extending from one of said side walls into said refuse chamber, said body having an open end communicating with the outside of said one of said side walls, a pair of ceramic members fitting 65 against each other with a portion of each fitting into said open end, a heating element clamped between said ceramic members and extending within said hollow body 70

in spaced relation therewith, and releasable detent members to normally maintain said pair of ceramic members fitted into said open end with said heating element clamped therebetween, said detent members quickly releasing said ceramic members upon rotation of one of said members.

2. An electric heating unit for use in an incinerator comprising a flange plate, a hollow metal body extending from one side of said flange plate, said body having an open end which opens through said flange plate and communicates with the side of said flange plate opposite to said one side, a pair of ceramic members fitting against each other with a portion of each fitting into said open end, a heating element clamped between said ceramic members and extending within said hollow body in spaced relation therewith, and releasable detent members on said flange plate to normally maintain said pair of ceramic members fitted into said open end with said heating element clamped therebetween, said detent members quickly releasing said ceramic members upon rotation of one of said members.

3. An electric heating unit for use in an incinerator comprising a flange plate, a hollow metal body extending from one side of said flange plate, said body having an open end which opens through said flange plate and communicates with the side of said flange plate opposite to said one side, a pair of ceramic members fitting against each other to define a split body having a boss portion fitted into said open end of said hollow body, said split body having a projecting portion outside said hollow body with shoulders engaging said flange plate and outer flanges adjacent said shoulders and extending partially around the periphery of said split body, a heating element clamped between said ceramic members and extending within said

5 hollow body in spaced relation therewith, and releasable detent means on said flange plate and engaging said outer flanges to normally maintain said pair of ceramic members fitted into said open end with said heating element clamped therebetween.

4. An electric heating unit for use in an incinerator having side walls and comprising a hollow metal body secured to one of said walls and extending into said incinerator, said body having an end opening toward the outside, a pair of ceramic members fitting against each other to define a split body having a boss portion fitted into said open end of said hollow body, said split body having a projecting portion outside said hollow body provided with outer flange means extending partially around the periphery of said split body, said outer flange means limiting movement of said ceramic members into said hollow body, a heating element clamped between said ceramic members and extending within said hollow body in spaced relation therewith, and releasable detent means carried on said one side wall and engaging said outer flange means to normally maintain said pair of ceramic members fitted into said open end with said heating element clamped therebetween.
